UNITED STATES PATENT OFFICE.

HENRY A. AMMANN, OF SPOKANE, WASHINGTON, ASSIGNOR TO DIAMOND INDIVIDUAL TOWEL SYSTEM CO., OF SPOKANE, WASHINGTON, A CORPORATION OF WASHINGTON.

TOWEL-RACK.

1,248,984.

Specification of Letters Patent.

Patented Dec. 4, 1917.

Application filed May 10, 1915. Serial No. 27,115.

To all whom it may concern:

Be it known that I, HENRY A. AMMANN, a citizen of the United States, residing at Spokane, in the county of Spokane and 5 State of Washington, have invented certain new and useful Improvements in Towel-Racks, of which the following is a specification.

This invention relates to improvements 10 in towel racks and cabinets and dispensing means, and has to do particularly with racks containing a shelf or case for clean towels and a receiving basket or container for soiled towels. 15 One of the objects of the invention is to provide for so arranging clean towels in bundles so that any desired quantity may be delivered to the consumer, such quantity being sufficient to supply a clean individual 20 towel for each user.

Another object is to provide a means for stringing towels of such construction that no prohibitive expense is incurred, this result being gained by using the device hereinafter shown, over and over again.

A still further object is to cut down the chances of towels being lost by the renting company through petty thievery and providing a guiding means to deliver the towels 30 from a supporting shelf to a receiving basket, such means operating to present a clean fresh towel to the next user.

It is a still further object to provide individual linen towels which will supersede 35 the more or less commonly used paper towels which are comparatively expensive, as once used they have to be thrown away. Individual linen towels are much more satisfactory and makes possible the use of same 40 in such a manner that an operating company may compete and keep down the cost of handling and for that purpose this invention has its prime object.

Other features and objects of the invention 45 will be more fully described in connection with the accompanying drawings and will be more particularly pointed out in and by the appended claims.

In the drawings:—

50 Figure 1 is a perspective view of my improved towel rack and attachment.

Fig. 2 is a view in front elevation of one of the members of my invention.

Fig. 3 is a view in side elevation of Fig. 2.

Fig. 4 is a fragmentary view of one of the 55 bottom slat members of the receiver, showing the manner of attachment of the lower end of the guiding wire.

Fig. 5 is a view partly in section of my 60 wire clamping device for preventing towels from being unstrung for the purpose of theft.

Like characters of reference designate 65 similar parts throughout the different figures of the drawings.

As illustrated 10 designates a towel rack which is shown in the form of an upright standard supporting near its upper end a 70 towel receiving compartment 11 for fresh thereof consisting of a receiver 13 for the used linen 14.

Attached to the receiving compartment 11 to the right of the center thereof is a 75 metal standard 15, being supported thereto on the shelf member 16 by lugs 17 and 18 positioned above and below 16. The standard 15 is secured to the shelf member 16 of the receptacle 11 by such means as screws 19. The upper end of the standard 15 supports 80 a ring 20, the purpose of which will be hereinafter fully described.

The towels 12 and 14 are threaded or strung on a wire 21, the end 22 of which is sharpened as shown in Fig. 4, to allow the 85 point to pass freely through a pack of towels. Permanently formed on the opposite end of the wire 21 is an eye 27 for engaging with a snap hook 28 located at 29 on the under side of the shelf member 16 of 90 the towel receiving device. From this snap hook 29 the wire passes, when in position on the towel rack, across the under side of the shelf to a hole through the member 18 of the upright standard 15, thence through 95 a similar hole provided in 16, thence through the pack of towels 12, from the receiving member through the ring 20 and downwardly into the receiving portion 13 of the rack. The ring 20 holds the wire in position 100 irrespective as to whether or not the wire happens to be too long, or longer than the normal or required length, which sometimes might happen and furthermore, the wire is maintained with a predetermined amount of 105 slack and because of the fact that the wire cannot get away from the ring, which latter forms a guide, the ring is more positive

than the fork which is shown in my Patent No. 1,181,983, issued May 9, 1916. Furthermore the ring 20 permits the user to insert his hand therethrough to more readily grasp the uppermost towel and the ring provides a larger opening through which the towel may be withdrawn than does the fork in my prior patent. On the lower end of the wire is placed at the time the towels are made up at the laundry a locking device 23 which is provided with a passage 24 to receive the wire. A locking member consisting of a screw with a triangular head serves to hold the wire in fixed relation with 23. Said locking device being countersunk so that a pair of pincers or wrench cannot be applied to remove same from the wire. The screw 25 will be operated by means of a key wrench (not shown) which will be in possession of authoritative parties only, thus it will be impossible to effect the removal of towels between the time they have left the laundry and their return.

On the lower end of 23 is an elongated opening 26, the lower end of locking member 23 being comparatively thin, 26 will thus be in the form of an eyelet which may be fastened to the bottom slats 27 of the receiver by the snap hook 28. The wire should have sufficient slack in it to enable the user to have plenty of freedom in using the towel while it still remains attached to the wire. As different conditions of slackness are necessary it is possible to have the wire 21 of sufficient length so that the member 23 may be locked at any predetermined position or may be altered at will by those having the key to the same, to give a comparatively close adjustment of the wire or a comparatively slack adjustment of same.

A method of supplying the rack and using the towels is as follows:—A suitable number of clean towels, usually one or two hundred, will first be threaded in any desired manner on the wire 21 and slid down the wire until the first one strikes the eye 27 which will act as a stop. The long length of free wire remaining will then be wrapped around the bundle of towels aiding their transportation to the consumers. When an empty rack is to be supplied the wire is unwound from the pack of towels and the end 27 is thrust through the hole 30' in the shelf 16 and through the hole 30 in the lug member 18 of the upright 15 and the eye engages with the snap hook 28 located on the under side of 16. The towels may then be placed upon the receiver shelf 16, the other end of the wire run through the member 20 and the eye end 60 of locking member 23 be snapped to 28 which will hold it in substantial and usable position until removed. 23, having previously been attached to the wire when the bundle of towels were made up, will now be adjusted to give the desired tension or slackness

on the wire to provide a free use or restricted use of the towels as desired.

The towels are now ready to use and if a person desires to make use of a towel he must slip his hand through the center or ring 70 20, take a towel from the rack and draw it through the ring, use it, then drop it and let it slide into the receiver 13. This operation may be repeated until the towels are all used.

It is my intention to have wires of such 75 quality that their use will be unlimited and that they will be interchangeable and usable on any similar rack and fixtures in service.

It is believed that the utility and the advantages of my invention will be clearly 80 understood from the foregoing description and while I have herein shown and described one specific form of my invention I do not wish to be limited thereto except for such limitations as the claims may import. 85

I claim:—

1. In a means for supporting and dispensing towels, a supporting rack, a ring member extending at right angles and perpendicular thereto and attached to said supporting 90 rack, a wire passing through said ring, one end of said wire being sharpened and locked in the lower receiving portion of the rack and one end of the wire being passed downwardly through the upper support and being 95 snapped to the lower side thereof, substantially as described.

2. In a device of the class described, a towel holding wire, a ring member through which wire is trained, said ring member having lugs 100 extending above and below said supporting rack, means for attaching said ring member to said rack, means for attaching said wire to the lower side of the upper towel receiving member, a locking member adjustably 105 engaging with the opposite end of the wire and a means for attaching said locking member to the bottom slats of the lower receptacle, said locking member being provided with a set screw to lockably engage 110 with the wire and constructed to receive a key wrench for operating it, substantially as described.

3. In a towel holder, upper means for supporting a stack of clean towels, a receiver below said means for the used towels, wire strung through the pack of towels, a device for anchoring said wire on said means, and a device for anchoring the remaining end of the wire into said receiver with sufficient 115 slack of the wire to render the same flexible under use, said wire passing through a ring upright member supported on the receiver, substantially as described.

4. In a towel holder, upper means for supporting a stack of clean towels, a receiver below said means for used towels, an anchored wire strung through the pack of towels, thence through the supporting shelf, a ring guard for the wire, the remaining end 125 130

of the wire passing through said ring, a locking device for anchoring the remaining end of the wire in said receiver, said locking device provided to adjust the slack of 5 the wire to render the same flexible under use, substantially as described.

5. As a means of protecting individual towels in transit from the laundry to the place of use and vice versa, a flexible stringer 10 having a sharpened end for insertion through a stack of initially imperforate clean towels at the laundry and provided on its remaining end with an enlargement to prevent the towels from being strung off 15 from said remaining end, and a locking enlargement for attachment to the sharpened end of said stringer, whereby the towels are locked against removal endwise off from the stringer in transit to and from the place of 20 use and at the place of use, said locking enlargement being removable whereby clean towels may be strung onto said stringer and soiled towels strung off from said stringer, substantially as described.

25 6. In combination, a towel rack having anchoring elements, and a flexible stringer.

adapted to be strung through a stack of clean towels at the laundry, said stringer having devices for locking the towels against endwise removal off from the stringer in 30 transit to and from the rack, and each of said devices having means for attachment to one of said elements, whereby a stringer with clean towels or a stringer with soiled towels may be attached to or detached from said rack, respectively, with the clean or soiled towels locked on the stringer, substantially as described.

7. As an article of manufacture, of the class described, a locking enlargement for 40 attachment to a flexible individual towel stringer comprising a body having a wire receiving bore, a locking member having threaded engagement with said body for projection into said bore, and said body having an eye, substantially as described.

In testimony whereof I affix my signature in presence of a witness.

HENRY A. AMMANN.
